SHEET DELIVERY MECHANISM FOR
PRINTING MACHINESWilliam F. Huck, Forest Hills, N. Y., assignor to
Huck Co., New York, N. Y., a partnership

Application February 24, 1948, Serial No. 10,235

18 Claims. (Cl. 271—79)

1

This invention relates to printing machines and more particularly to the delivery mechanism attached to such machines, whereby sheets that have previously been printed, or otherwise processed in sheet or web form are laid down flat and stacked in a pile.

The speed, at which a printing or other process can be carried on, determines to a large extent the price that has to be charged for the finished product. If the processing machines have to operate at a slow speed, the cost of the finished product is necessarily high, but if the processing machines can be operated at a high rate of speed, the cost of the product will be low. Therefore it is desirable that printing and other sheet processing machines be operated as fast as possible. It has been found that the speed at which flat sheets can be delivered, after they have been processed, often determines the speed at which a whole processing machine can operate. Mechanisms now in use for delivering sheets from printing machines have left much to be desired in that they are slow and thereby limit the printing or other processing speed. This is especially true when large sheets are being handled. Therefore, it is a primary object of this invention to provide a new and improved delivery mechanism that will receive and deliver sheets at a speed much above the speeds now commonly attained.

Another object of the invention is to provide a new and improved delivery mechanism which will form neat and accurate piles of sheets at a very high rate of speed.

A further object of the invention is to provide a new and improved means for speeding up the movement of grippers whereby they can be made to receive a sheet while it is being carried by a fast moving cylinder.

A still further object of the invention is to provide a new and improved means for controlling the tail-end of sheets in a delivery mechanism.

Other important objects of this invention will be apparent from the following description and appended claims.

A practical embodiment of the invention is represented in the accompanying drawings in which:

Figure 1 is a side elevational view showing a section of a machine embodying this invention and taken along the irregular line 1—1 of Figure 2;

Figure 2 is a plan view partly in section and taken substantially along the line 2—2 of Figure 1;

Figure 3 is a diagrammatic representation of the various positions assumed by parts of the

2

conveyor mechanism while conveying a sheet; and

Figure 4 is a fragmentary view, taken along the line 4—4 of Figure 1, showing the cam blocks and cam rollers.

For a more complete understanding of my invention and how it operates, to increase the speed of delivering sheets, reference should be made to the accompanying drawings, wherein I have shown a new and improved sheet delivery mechanism comprising a pair of spaced main side-frames 11 and 11'. These side frames may be supported from the floor or may be connected to any type of sheet processing machine, as for example, a printing machine. Frames 11 and 11' support a plurality of instrumentalities including a pair of rotatably mounted cutting cylinders 12 and 13 each having cutting knives 14 that may be used to cut sheets from a web W. It will be understood that the cutting cylinders 12 and 13 form no part of the present invention, per se, and are shown simply to indicate that my delivery mechanism is capable of receiving sheets cut from a fast moving web. If the processing or printing machine operates on sheets instead of a web, the cylinders 12 and 13 are eliminated or otherwise silenced. The frames 11 and 11' support, among other items, a plurality of tape carrying idler rollers 16 and a fast rotating delivery cylinder 17. Tapes 18 and 19 pass over the rollers 16 and also pass around and thus are driven by the cylinder 17. The tapes 18 and 19 receive and forward sheets in proper register with a cut-out 21 formed in the surface of the cylinder 17. The method of registering these sheets is not herein shown or described in detail, because any satisfactory known registering means may be used. The surface of the cylinder 17 is perforated with a multiplicity of closely spaced holes 22, and the interior of the cylinder is exhausted to a pressure below atmospheric pressure by means later to be described. Thus, sheets S fed by the tapes 18 and 19 are held to the surface of the cylinder 17 by suction. The frames 11 and 11' also support a pair of stationary spacers 23 and 23', the spacer 23 being secured to frame 11 by screws 24, and the spacer 23' being secured to frame 11' by screws 24'. A cam block 26 is secured to the spacer 23 by screws 27, and a second cam block 26' is secured to the spacer 23' by screws 27'. A cross shaft 28 is rotatably supported in both of the cam blocks 26 and 26' and at the same time one end 29 of this shaft is journaled in the side-frame 11', and a plurality of other parts, some of them rotatably mounted, are carried by the cam

blocks 26 and 26'. This results in the two outside frames supporting a plurality of rotating members and a pair of stationary cam blocks, which in turn support additional rotating members later to be described.

A means for driving the mechanism herein disclosed is provided. This drive includes a gear 31, which, preferably, is driven by the printing or other processing machine (not shown), which machine, it will be understood, feeds sheets to the delivery mechanism under consideration. Gear 31 meshes with and drives a gear 32 keyed to one end 33 of the shaft of the delivery cylinder 17. The other end 33' of cylinder 17 has a small gear 34 keyed to it. Gear 34 drives a large gear 36 keyed to the end 29 of the shaft 28, and thus drives the shaft 28 at a reduced ratio of say 4 to 1. It will be noted that the shaft 28 is positioned axially by the gear 36 and a collar 37. A pair of sprockets 38 and 38' are keyed to and thereby are driven by the shaft 28. Sprocket 38 is located between the frame member 11 and the cam block 26, whereas, the sprocket 38' is located between the frame member 11' and the cam block 26'. The sprockets 38 and 38' respectively carry and drive link chains 39 and 39', which in turn drive a pair of sprockets 41 and 41' keyed to opposite ends of a shaft 42; the said shaft 42 being rotatably journaled in the cam blocks 26 and 26'. As best seen in Figures 1 and 3, the paths of the chains 39-39' are semi-circular as they pass over the sprockets 38-38' and 41-41' respectively. The paths of the chains 39-39' between the sprockets are straight parallel lines. The shaft 42 is properly positioned with respect to the cam blocks by a pair of spaced collars 43 and 43' which are held to the shaft 42 by suitable set screws. It will be noted that the hereinbefore described driving mechanism is such that, when the delivery cylinder 17 (as seen in Figure 1) is turning clockwise, the shafts 28 and 42, as well as the sprocket wheels mounted thereon, will be turning counterclockwise. This results in the top reach of the chains 39 and 39' travelling from right to left as viewed in Figures 1 and 3, while the bottom reach of the chains travels from left to right. The front and back chains 39 and 39', as they travel around the sprockets, carry with them a plurality of evenly spaced gripper structures 44.

All of the gripper structures are identical and, therefore, only one will be described. Each gripper structure spans the space between the two chains; the front end of the structure being supported from the chain 39 by a long special chain-pin 46 which replaces one of the standard pins in the chain. The pin 46 is journaled in a substantially U-shaped member having outside and inside arms 47 and 48 respectively, which are positioned in planes parallel to the chain 39. Inside arm 48, in addition to supporting the pin 46, has a branch which carries an inwardly projecting pin 49 which acts as an axle for a front cam roller 51. At a point remote from the pin 49, the arm 48 joins an extension 52 which is normal to the chain 39. The arm 52 journals a gripper shaft 53, to the outer end of which is secured a cam lever 54 which by means of a pin 56 rotatably supports a cam roller 57. At a point remote from the arm 48, the extension 52 joins an intermediate portion of a front connecting bar 58. Opposite ends of the bar 58 support cross members 61 and 62, whereas a portion of bar 58 between the extension 52 and the member 61 carries an outwardly facing pin 63 which

rotatably carries a cam roller 64. The cross members 61 and 62, as well as the gripper shaft 53, extend transversally of the delivery mechanism to a point where they join a rear connecting bar 58', which carries a pin 63', a roller 64', an extension 52', as well as arms 48' and 47' for supporting a long pin 46', a pin 49' and a roller 51'. The parts just designated by primed numerals are equivalents, except for being opposite hand, to parts previously designated by the same un-primed numerals. It will be understood that the spaced opposite ends of each one of the identically constructed gripper frames are supported from and carried along by the chains 39 and 39'. Each of the previously described cam blocks 26 and 26' is provided with a pair of cam grooves on opposite side faces thereof. These cam grooves as best seen in Figures 3 and 4 are closed paths along which the plurality of cam rollers travel. Block 26 has an out-facing groove 66, which guides cam roller 51, and also has an in-facing groove 67 which guides roller 64. Block 26' has an in-facing groove 68 which guides roller 64' and an out-facing groove 69 which guides roller 51'. From Figure 1 it will be noted that the path of the cam grooves 66 and 67 can and do cross one another without interference; in like manner cam grooves 68 and 69 cross one another without interference. The gripper shaft 53, where it extends between the connecting bars 58 and 58', carries a plurality of spaced grippers 71 which are biased, by a spring (not shown), to a position where their distal or free ends are held in contact with the cross bar 62.

The configuration of the cam grooves 66, 67, 68 and 69 are such that the special pins 46 and 46' remain on the path of the chains at all times as the chains travel over the sprockets 38, 38', below the spacers 23 and 23', around the sprockets 41, 41' and over the spacers 23 and 23'. As each gripper structure 44 successively swings around the center line of the shaft 28, and thus the center of the sprockets 38 and 38', the angular acceleration and velocity, controlled by the cam grooves 66, 67, 68 and 69, of the structure 44 is such that the cross member 62, and the ends of grippers 71 contacting therewith, will move at a speed that, at least for a short period of time, is equal to the peripheral or surface speed of the delivery cylinder 17. The position and size of the sprockets 38 and 38', and the length and configuration of arms 48-47-58 are such, with relation to the surface of the cylinder 17, that, when the ends of the grippers 71 are travelling at the same speed as the surface of the cylinder 17, they will also be positioned in the cut-out or recess 21 provided in the cylinder 17. Furthermore, a gripper cam 72 held to the frame 11 by screws 74 is so located, constructed, and arranged that it will be contacted by the roller 51, and thereby operate the grippers 71 at just the proper instant. Those versed in the art will realize that each gripper, as it thus accelerates to the surface speed of the cylinder 17, grips the leading end of the sheet S currently being presented by the delivery cylinder 17. As soon as the leading end of the sheet has been gripped, the gripper bar 62 slows down or decelerates to a speed that is about $\frac{1}{2}$ of the speed it had when it was travelling at the surface speed of the cylinder 17. This deceleration is obtained by the proper configuration of the cam grooves 66, 67, 68 and 69. In the preferred embodiment of the invention this reduced speed is reached just about the time that the special long pins 46-46' pass from their curvi-

linear path, to the straight path at the bottom of the sprockets 38-38'. Each time the cylinder 17 completes a rotation and thus carries a sheet forward one of the plurality of gripper structures 44 will take a sheet from the cylinder 17.

A more complete understanding of the movement of the gripper structures 44 and the grippers carried thereby can be had by reference to the diagrammatic representation shown in Figure 3. In this drawing the path of the chain 39 is represented by a solid line carrying dots. The path of cam roller 51 and the groove 66 is represented by a dash-dot-dot line, and the path of the cam roller 64 and the groove 67 is represented by a dash-dot line. The path of the gripper cross member 62 is represented by a closed solid line. The left portion of Figure 3 shows the gripper structure 44 as it is speeded up so as to cause the gripper to move at the surface speed of the cylinder 17, and then slowed down again. On this portion of Figure 3 the gripper structure is moving counterclockwise around the shaft 28, in position I of Figure 3 the gripper structure is shown to form an angle of minus forty degrees (-40°) with a vertical center line. In the next shown position II this angle has been reduced to minus thirty degrees (-30°). This is caused by a change in direction of the cam grooves 66 and 67. The line from the center of the sprocket 38 and shaft 28 through the long chain pin 46 forms an angle of minus forty-three degrees (-43°). This indicates that the position of the structure 44 is angularly dependent solely on the cam grooves 66 and 67. The next position III shows an angle of plus fifteen degrees (+15°) with the vertical center line and minus thirty degrees (-30°) with the sprocket center line passing through the pin 46. At position IV the cross member 62 of the structure 44 has its highest velocity and now forms an angle of plus seventy-seven degrees (+77°) and passing exactly on the radial line from the sprocket to the pin 46. In observing the distances travelled by the gripper 62-71 between positions I, II, III, IV, it will be noted that these distances progressively become greater despite the fact that the distances between the successive positions of the pins 46 from position to position are in all cases the same. The next position V forms an angle of plus one hundred thirty-seven degrees (+137°) with the vertical center line, an angle of plus thirty degrees (+30°) with the radial center line through the sprocket center and pin center 46. Positions VI, VII and VIII indicate how the displacement of the grippers become less and less as the gripper structure passes from position VI to position VIII. In other words the grippers are accelerated from positions I to IV and are decelerated from position IV to position VIII. In the right portion of Figure 3 the positions IX and X indicate the approach of the sheet S and the grippers 62-71 to delivery position. In position XI the cam groove 66 raises the roller 51 while the cam groove 67 lowers the roller 64 thus causing the gripper structure 44 to have a clockwise angular motion around the pin 46. This slows down the linear speed of the cross member 62 and the gripper 71. Position XII indicates the extreme clockwise position of the structure 44 around the pin 46, with the roller 51 in high position and the roller 64 in the lower position. From here on the cam paths 66 and 67 rotate the structure 44 through positions XIII, XIV, XV, XVI, XVII, XVIII, and XIX to the upper horizontal portion of the conveyor.

It will be noted that this arrangement permits controlled angular accelerations of the conveyor structure 44 around pin 46 in accordance with a desired mathematical formula. This results in a conveying motion that is free from impacts and abrupt application and cessation of acceleration forces. Furthermore this conveyor mechanism permits a considerable speeding up as well as slowing down of the gripper structure which would not otherwise be possible.

It will be understood that the above described motion could also be obtained to a limited degree by providing only one roller, either roller 64 or roller 51, with its corresponding cam path, and by guiding pin 46 in a path following that of the chain 39.

In order to be able to control the many sheets that are taken by the grippers, I have provided an enclosure member or housing indicated, generally, by the numeral 81. This housing has an angled upper wall 82, that extends from a position 83 just under the path of the sheets S as they approach the cylinder 17, to a point 84 where it joins the top of a fan casing 86. This wall 82 is apertured, as at 87, to allow the tapes 19 to pass therethrough. The bottom of the housing is closed by a reverse curved wall 88, that extends from the under part of the fan casing 86 to a position 89 where it acts as a guide member for guiding one side of a pile of sheets 91. The two sides of the enclosure member are formed by side walls 92 and 93. The fan casing 86 supports a motor 94 having an impeller 96 which functions to exhaust air or other fluid medium from the bottom portion of the enclosure 81 and thereby create a comparatively slow moving column of air or other fluid which flows through the openings 22 in the cylinder 17 down through the enclosure 81 and out past the fan impeller 96. The flow of air through the enclosure may be regulated by varying the speed of the motor 94, or, as I have chosen to show, by providing a movable baffle plate or damper 97, that is pivoted on a shaft 101 to which is secured a lever 103 controlled by a link 102. The link 102 is under the control of a governor, or other speed controlling means, as for example controller 105 associated with the machine that processes or prints the web W, or sheets S, before they reach the cylinder 17. Thus the amount of air handled by the fan 96 is a function of the speed of the printing or other processing machine.

After the grippers 71 have reached below the front or leading edge of a sheet and thereby gripped the sheet, the leading edge of the sheet is carried forward and assumes the successive positions indicated in Figure 1 by the letters b, c, d, e, f, g, h, i, j, k, l and m. The successive positions of the trailing edge of the sheet are indicated by the letters e', f', g', h', i', j', k', l', and m'. As the leading edge of the sheet approaches the point p, the configuration of the cam grooves 66, 67, 68, and 69 is such that the grippers 71 and member 62 slow down to substantially a momentary standstill; this being indicated by the letters p, q and r in Figure 1. At this point a stationary cam block 104 engages the cam roller 57 and releases the sheet so that it is dropped onto the pile 91. The pile is guided by the stationary guards 89 and a pivotally mounted guard 106. A means for removing a sheet from the pile 91 for

inspection is provided, and includes a shaft 107 journaled in frame supported brackets 108. A hand lever 109 is secured to the shaft 107 and is biased counterclockwise (Figure 1) by a spring 111. A transparent guard 112 encloses the right end (Figure 1) of the mechanism and thus protects an operator who may use the lever 109.

The fan 96 and the housing 81 assists in controlling the movement of the sheets as they move from the cylinder 17 to the pile 91. The fan 96 evacuates the cylinder 17 and thus causes the sheets to be held to the upper surface thereof as the cylinder rotates clockwise as seen in Figure 1. The uniformly and comparatively slow moving air column in the enclosure 81 tends to pull each sheet lightly into the enclosure until the tail of the sheets is released from the cylinder 17 and the tapes 19. The main body of moving air, which moves in a direction substantially perpendicular to the main body of the sheets S, then pulls the tail of the sheet through the successive positions b', c', d', e', f', g', h', i, j, k', l', m' until the sheet conforms to the curved wall 88. At all times, and even after the sheets are on the wall 88, the sheets are separated from one another by a quantity of air as it moves from the mouth of the enclosure, as defined by the position 83 and the position 89, toward the fan 96.

An observation of Figure 1 will show that speed of the trailing end of the sheet, when it moves from a position f' to a position m', will be greater than the speed of the leading end of the sheet, as it moves from the position f to the position m. However, when the trailing end of the sheet arrives at the position m', it will be seen to be moving at substantially the same speed as the leading edge of the sheet at position m.

Figure 4 shows one of the set of cam blocks 26-26' which is satisfactory for one sized sheet and one particular set of operating conditions. It will be understood that cam grooves of other configuration and other changes in design may be used in the above described mechanism without departing from the spirit of the invention.

The operation of the device will be understood from the above detailed description of the mechanism, however, the following resume will help toward a complete understanding of my invention. A sheet S, which may be fed as such or which may be cut from the web W, is guided around the cylinder 17 by the tapes 18-19 and the sheet is held to the cylinder 17 by suction produced by the fan 96. The leading end of the sheet will be in proper register with the indentation 21 of the cylinder 17. The grippers 71-62 are so timed that the front or leading edge of the sheet will be gripped at the proper instant by the gripper 71. The uniform speed of the sprockets 36-32' and the chains 39-39', as they move, the gripper structures 44 past the cylinder 17 is amplified, first by the distance that the grippers are from the center of the sprockets, and also by the coaction of the cam rollers 51-51' and 64-64' controlled by the cam grooves 66, 67, 68, and 69, which are so constructed and arranged so as to be additive and thereby obtain a gripper speed that is equal to the full speed of the sheet S as it is carried by the cylinder 17 at the instant the grippers take the sheet. The motion of the grippers, and therefore the motion of the leading edge of the sheet is gradually reduced to say one-fifth of the surface or peripheral speed of the cylinder 17. Thereafter the speed of the forward edge of the sheet remains substantially constant until the grippers reach

the points indicated by the points p, q, and r, at which point the cam grooves 66, 67, 68, 69 cause a partial reverse action to take place at the gripper. This in turn causes the speed of the leading edge of the sheet to drop practically to zero. At this point the cam 104 contacts roller 57 and thereby opens the grippers releasing the sheet and allowing it to drop onto the pile 91. The grippers thereafter are carried around the upper per each of the chains 39-39' to return to the cylinder 17 for another sheet. While the grippers successively pass through the points indicated by the letters b, c, d, . . . to m, the slow moving air column in the enclosure 81 controls the tail of the sheet S in a manner previously described.

The speed of the printing or other processing machine will control the position of the damper blade 97 and thus obtain the proper amount and speed of air.

While I have illustrated and described a preferred embodiment of my invention, it will be understood that the invention may be otherwise embodied and practiced within the scope 25 of the following claims.

What I claim as new and desire to secure by Letters Patent of the United States is:

1. A delivery mechanism, comprising, a sheet presenting member moving at a high rate of speed 30 and in a predetermined direction; a plurality of sheet gripping mechanisms, each gripping mechanism having a gripper arranged to grip a sheet; means moving at a uniform rate of speed that is slower than the speed of said sheet carrying member, said means being connected to and moving said gripping mechanisms successively toward a sheet gripping position adjacent to said sheet presenting member and at said position moving said sheet in the same general direction that said 40 sheet presenting member is moving; a cam follower secured to each of said sheet gripping mechanisms; a cam adjacent to the means moving at the uniform rate of speed and having an irregular path, which cooperates with the cam followers, to move each gripper during its gripping operation at a speed greater than the speed of said uniformly moving means and equal to the speed of the high speed sheet presenting means, said cam having, remote from said first path, a 50 second path which cooperates with the cam follower to move each gripper substantially to a standstill; means for causing said grippers to grip the sheet while moving at the high rate of speed; and means for causing said grippers to release the sheet when they are substantially at a standstill.

2. A delivery mechanism, comprising, a sheet carrying member moving at a uniform high rate of speed and presenting sheets moving in a predetermined direction and at the same high rate of speed as said sheet carrying member; a relatively heavy conveying member continuously moving toward a location adjacent to said sheet carrying member and traveling at a uniform speed that is slower than the speed of said sheet carrying member, and thus slower than the speed at which said sheets are moving when presented, and said conveying member at at least one location moving in the same general direction as said sheet; a plurality of light weight frames having pivotal portions pivotally connected to said conveying member and thus carried along in the same direction and at the slow speed of said conveying member; gripper means secured to each frame at locations remote from the pivotal 70 mounted portions thereof; a cam follower secured

to each of said frames; a cam adjacent to said conveying member and having an irregular path which cooperates with said cam followers as said heavy conveyor member successively carries each frame adjacent to said sheet carrying member, the said cam acting on each cam follower to pivot each frame in such a direction as to change the speed of movement of said gripper from the slow speed of said conveying member to the higher speed of said sheet carrying member; and means causing each gripper means to grip a sheet at the time the gripper means is moving at the speed of said fast moving sheet.

3. A delivery mechanism constructed in accordance with claim 2; the cam of said mechanism having at a second location an additional irregular path which cooperates with said cam followers to pivot each frame about its pivotal portion in such a direction as to slow down the movement of each gripper means from the high speed of said sheet carrying member to the speed of said slower moving conveyor member.

4. A delivery mechanism constructed in accordance with claim 2; the cam of said mechanism having, at a second location, an additional irregular path cooperating with said cam followers to pivot each frame about its pivotal portion in such a direction as to slow down the movement of each gripper means from the high speed of said sheet carrying member to the speed of said slower moving conveyor; the cam of said mechanism having, at a third location, an additional irregular path cooperating with said cam followers to pivot each frame about its pivotal portion in such a direction as to slow down the movement of each gripper means from the speed of said conveyor member to a speed substantially equal to zero; and means operating each gripper means to release the sheet at the time each gripper is moving at the speed that is substantially equal to zero.

5. A delivery mechanism for delivering a sheet, comprising, a high speed sheet-carrying-member having a center, and rotating and carrying the sheet in a predetermined direction about said center; a uniformly moving conveyor having a second center adjacent to said first center, said conveyor moving in a well defined path at a predetermined base rate and successively having spaced portions that approach said sheet-carrying member and turn about said second center in a rotational direction opposite to that of said sheet-carrying-member; a plurality of frame members having pivots pivotally connected to said spaced portions of said conveyor and said frame members having portions remote from said pivots; an irregularly shaped path-member adjacent to said conveyor and cooperating with and moving the remote portions of said frame members to increase the speed of said remote portions of the frame-members as they approach said sheet-carrying-member; and grippers carried by the remote portions of said frame members and receiving said sheets from said sheet carrying member when the remote portions are moving at the increased speed.

6. A delivery mechanism for delivering a sheet, comprising, a high speed carrying delivery cylinder presenting a sheet moving in a predetermined direction at a high speed, said cylinder having a plurality of holes formed in the peripheral surface thereof; a pair of uniformly moving chains operating at a speed that is less than the speed of said sheet and in a path which at least one location extends in the same direction as said

sheet is moved; a plurality of gripper-structures each having a portion pivotally connected to spaced portions of said chains; a sheet gripping mechanism formed on each of said gripper-structures and located remote from the portion pivotally connected to said chains; a cam-follower carried by each of said gripper-structures and positioned remote from said pivot and from said sheet gripping mechanisms; a cam, located adjacent to said chains, said cam guiding said cam followers and thereby pivotally moving said gripper-structures with respect to said chains as said chains move said gripper-structures, thus moving said sheet gripping mechanisms to sheet gripping relation with respect to said cylinder, and also moving said sheet gripping mechanisms, while in sheet gripping relation, at the same speed and in the same direction as said sheet; an enclosure having a mouth adjacent to said cylinder and to the path followed by said chains; a fan located in said enclosure and exhausting air from said enclosure and from said cylinder, the fan thereby producing suction in said cylinder and drawing the sheets into said enclosure; means regulating the amount of air exhausted by said fan; a cam located adjacent to said cylinder and causing said grippers to grip the sheet at the time the sheet gripping mechanisms are moving at the speed of said sheet; and a second cam located remote from said cylinder and releasing the sheets from the sheet gripping mechanisms when they are remote from the said enclosure.

7. A delivery mechanism, comprising, means for presenting a plurality of fast moving sheets having leading ends moving in a predetermined direction; a plurality of fast moving grippers moving in the same direction and gripping the leading ends of said sheets; a moving conveyor; a pivotal connection between each of said grippers and said conveyor; cam followers connected to each of said grippers; cam means adjacent to said conveyor and having an irregular path which cooperatively engages said cam followers, thereby, pivotally moving each gripper and thus slowing down the relative speed of said grippers with respect to said conveyor; and an air moving impeller moving air between the plurality of sheets as the leading ends thereof are slowed down, said air acting to keep the sheets separated one from the other and at the same time moving the un-gripped ends of the sheets.

8. A sheet delivery mechanism, comprising, a plurality of identical sheet grippers; a conveyor member moving at a uniform base speed; pivotal means mounting each of said grippers on said conveyor member; two cam followers connected to each of said sheet grippers; two cams adjacent to the said conveyor member, one cam having an irregular path which cooperates with one of the cam followers, and the other cam having an irregular path which cooperates with the other of said cam followers.

9. In a delivery mechanism arranged to grip a sheet moving in a predetermined direction at a high rate of speed and to deliver the sheet at a slow speed; a conveyor at least one location moving in the same direction as said sheet and at a constant base speed; a structure connected to and moved at the base speed by said conveyor as said conveyor moves; sheet gripping means connected to said structure and thus moved at the base speed as said structure is moved; guide means adjacent said conveyor and having an irregular path which cooperates with said structure; a portion of said path superposing an accelerating

force on said sheet gripping means as it is moved along by said structure and thereby causing said gripping means to move in the same direction as said sheet and faster than the base speed; another portion of said path remote from the first portion superposing a decelerating force on said gripping means as it is moved along by said structure and thereby causing said gripping means to move slower than said base speed; means operating the gripping means to grip a sheet when the gripping means is accelerated to a speed above the base speed and means operating the gripping means to release the sheet when the gripping means is decelerated below the base speed.

10. A delivery mechanism, comprising, means for presenting a sheet having a leading end moving in a predetermined direction at a high rate of speed; a conveyor moving in the same direction as the leading end of said sheet but at a slower speed; a frame pivotally connected to and carried along by said conveyor, said frame having a portion remote from where said frame is pivotally connected; a gripper carried by said remote portion of said frame; a cam roller carried by said frame at a location remote from where said frame is pivotally connected to said conveyor; and a cam adjacent said conveyor and having an irregular path which engages and cooperates with said cam roller in such a manner so that as said frame is moved along by said conveyor the irregular path of said cam acts on said cam roller to swing said frame about said pivotal connection in such a manner that said gripper carried by the remote portion of said frame is moved in the same direction and at a speed equal to the speed of said sheet at the time said gripper grips said sheet.

11. A delivery mechanism, comprising, a high speed sheet carrying member arranged to present a sheet in a predetermined direction at a high speed; a uniformly moving conveyor moving in the same direction as said sheet and at a speed that is slower than the presentation speed of said sheet; at least one frame; at least one pivotal member carried by said conveyor and pivotally attaching said frame to said conveyor; at least one cam roller carried by said frame; at least one gripper carried by said frame at a location remote from said pivotal member; and an irregularly shaped path member adjacent to said conveyor and in cooperative engagement with said cam roller, the shape of said irregular path being of such a configuration that said frame as it is moved along by said conveyor is also moved about said pivotal member by said cam and cam roller in such a manner as to cause said gripper to move in the same direction and at a speed equal to the speed of said sheet; and means causing said gripper to grip said sheet while it is moving in the same direction and at the speed of said sheet.

12. A delivery mechanism for delivering a sheet, comprising, a sprocket rotating in a chosen direction; a chain carried by said sprocket; at least one gripper structure pivotally connected to said chain and thus carried along and in the same direction as said chain; a high speed sheet carrying cylinder positioned adjacent to said sprocket and rotating in a rotational direction opposite to that of said sprocket, said high speed cylinder delivering sheets moving in one direction to a location between said cylinder and said sprocket; at least one gripper carried by said gripper structure; a cam roller carried by said gripper structure; and a cam groove adjacent to the chain and having an irregular path in which the cam roller

tracks, said cam groove having such a configuration that said gripper structure is given pivotal movement in addition to the movement it receives from said chain thereby causing said gripper when it grips the sheet delivered by said cylinder to move at a speed faster than the speed of said chain and in the same direction as and at substantially the same speed as the sheet being gripped.

13. In a sheet delivery mechanism; a member moving at a uniform rate of speed; a gripper-frame; a pivot mounting said gripper-frame on said member; a gripper carried by said gripper-frame at a point remote from said pivot; a pair of cam followers carried by said gripper-frame at locations remote from said pivot; and two cams adjacent said member, the paths of said cams crossing and recrossing each other, and one of said cam followers cooperating with each of the cams.

14. A sheet delivery mechanism in accordance with claim 13 in which a cam block is provided and in which one of the cams is on one side of the cam block and the other cam is on the other side of the cam block.

15. A delivery mechanism in accordance with claim 2 in which said light weight frames which carry the gripper means are pivotally connected at closely spaced intervals along the conveying member; and in which an enclosure is provided having an opening adjacent to said sheet carrying member and said heavy conveying member; and into one portion of which enclosure the gripper means successively move the forward ends of the sheets with the main body of the sheets in superposed position; and a fluid exhausting mechanism located in another portion of said enclosure, thereby exhausting fluid from said enclosure and pulling the tail ends of said sheets into said enclosure.

16. A delivery mechanism in accordance with claim 2 in which said light weight frames which carry the gripper means are pivotally connected at closely spaced intervals along the conveying member and thus placing the gripper means at closely spaced intervals so that sheets held by said gripper means will be closely spaced and in superposed position; and in which an enclosure is provided having two openings, one of said openings being adjacent to said sheet carrying member and said heavy conveying member, and past the one opening of which the gripper means successively move the forward ends of the sheets; and a fluid exhausting mechanism located adjacent the other opening of said enclosure thereby exhausting fluid from said enclosure and causing fluid to be drawn between the plurality of superposed sheets as they are moved from the location where said sheets are gripped.

17. A delivery mechanism, comprising, a sheet carrying member moving at a uniform predetermined speed and presenting sheets moving in a predetermined direction and at the same speed as said sheet carrying member; a conveying member continuously moving toward a location adjacent to said sheet carrying member and traveling at a uniform speed that is different than the speed of said sheet carrying member, and thus different than the speed at which said sheets are moving when presented, and said conveying member at at least one location moving in the same general direction as said sheet, a plurality of frames having pivotal portions pivotally connected to said conveying member and thus

carried along in the same direction and at the speed of said conveying member; gripper means secured to each frame at locations remote from the pivotal mounted portions thereof; a cam follower secured to each of said frames; a cam adjacent to said conveying member and having an irregular path which cooperates with said cam followers as said conveyor member successively carries each frame adjacent to said sheet carrying member, the said cam acting on each cam follower to pivot each frame in such a direction as to change the speed of movement of said gripper from the speed of said conveying member to the speed of said sheet carrying member; and means causing each gripper means to grip a sheet at the time the gripper means is moving at the speed of said sheet.

18. A delivery mechanism comprising a sheet carrying member moving at a uniform predetermined speed and presenting sheets moving in a predetermined direction and at the same speed as said sheet carrying member; a conveying member continuously moving toward a location adjacent to said sheet carrying member and traveling at a uniform speed that is different than the speed of said sheet carrying member, and thus different than the speed at which said sheets are moving when presented, and said conveying member at at least one location moving in the same general direction as said sheet, a plurality of frames having pivotal portions pivotally connected to said conveying member and thus carried along in the same direction and at the speed of said conveying member; gripper means secured to each frame at locations remote from

the pivotal mounted portions thereof, pivoting means adjacent to the path of the conveying member and arranged to engage each of said frames in turn as they are carried by said conveying member adjacent to said sheet carrying member, and to pivot each frame in such a direction as to change the speed of movement of said gripper from the speed of said conveying member to the speed of said sheet carrying member; and means causing each gripper means to grip a sheet at the time the gripper means is moving at the speed of said sheet.
